[57] ABSTRACT

A cam assembly is mounted on an electrostatographic machine in contact with a structure bar of a pressure roller assembly. Upon activation of a motor, the cam shaft is caused to rotate through a suitable gearing arrangement thereby swinging the assembly about an axis to place the pressure roller in contact with the fuser roller. Upon reaching the end stop position, a solenoid is activated to lock by appropriate linkage the rollers in operational position. Upon deactivation of the solenoid the cam shaft is caused to rotate to its standby position by a torsional spring affixed to the shaft and to the support assembly.

APPARATUS FOR PLACING ROLLERS IN CONTACT IN A PRESSURE FUSER ASSEMBLY

BACKGROUND OF THE INVENTION

This invention relates to electrostatography, and more particularly to apparatus for placing a fuser roller and a pressure roller in contact in an electrostatographic apparatus.

In the practice of xerography as described in U.S. Pat No. 2,297,691 to Chester F. Carlson, a xerographic surface comprising a layer of photoconductive insulating material affixed to a conductive backing is used to support electrostatic images. In the usual method of carrying out the process, the xerographic plate is electrostatically charged uniformly over its surface and then exposed to a light pattern of the image being reproduced to thereby discharge the charge in the areas where light strikes the layer. The undischarged areas of the layer thus form an electrostatic charge pattern in conformity with the configuration of the original light pattern.

The latent electrostatic image may then be developed by contacting it with a finely divided electrostatically attractive material, such as a resinous powder. The powder is held in the image areas by the electrostatic fields on the layer. Where the field is greatest, the greatest amount of material is deposited; and where the field is least, little or no material is deposited. Thus, a powder image is produced in conformity with the light image of the copy being reproduced. The powder is subsequently transferred to a sheet of paper or other surface and suitably affixed, such as by heat, pressure, and the like, to thereby form a permanent print.

The toner may be fixed by passing the sheet of paper or other surface including the transferred image between a heated roller and a second roller in pressure contact therewith whereby the toner becomes fused to the sheet of paper by the combined effect of heat and pressure. The fuser roller is generally formed of a metallic substrate for high heat transfer efficiencies, whereas the second or pressure roller is formed with a flexible surface material to provide a sufficiently wide nip when placed in contact with the fuser roller to fix efficaciously the toner. Continued contact between the heated fuser roller and pressure roller is deleterious to the flexible surface material of the pressure roller when the machine is in a standby mode.

OBJECTS OF THE INVENTION

An object of this invention is to provide a novel fuser assembly for an electrostatographic machine.

Another object of this invention is to provide a novel apparatus for placing the fuser and pressure rollers in contact for an image transfer mode of an electrostatographic machine.

Still another object of the invention is to provide a novel apparatus for ensuring uniform pressure between the fuser and pressure rollers of an electrostatographic machine.

A still further object of the invention is to provide a novel cam loading assembly for placing the fuser and pressure rollers in contact for an image transfer mode of an electrostatographic machine and for separating such rollers for other modes thereof, e.g., when the machine is in a standby mode.

SUMMARY OF THE INVENTION

These and other objects of the invention are obtained by providing a fuser assembly including a fuser roller, a pressure roller mounting assembly, and a cam assembly operatively associated with the pressure roller assembly. The pressure roller mounting assembly is pivotally mounted to the frame assembly above the fuser roller mounted for rotation therein. Activation of the cam assembly causes the pressure roller mounting assembly to move downwardly to place the pressure roller in contact with the fuser roller. At the termination of the loading cycle, the cam assembly is locked in place. Upon release of the locking means, the force of torsion springs and the inertia of the cam causes the cam shaft to rotate thereby permitting the pressure roller to move away from the fuser roller.

DESCRIPTION OF THE DRAWINGS

20 A better understanding of the present invention as well as other objects and further features thereof will become apparent upon consideration of the following detailed disclosure thereof, especially when taken with the accompanying drawings, wherein like numerals designate like parts throughout.

25 FIG. 1 is a schematic sectional view of an electrostatic reproduction machine embodying the principles of the invention;

30 FIG. 2 is a side view of the pressure roller assembly illustrating the positioning of the pressure roller in an image transfer mode;

35 FIG. 3 is a partial sectional isometric view of the fuser assembly; and

40 FIG. 4 is an enlarged exploded isometric view of the cam assembly.

For a general understanding of the illustrated copier/reproduction machine in which the invention may be incorporated, reference is had to FIG. 1 in which the various system components for the machine are schematically illustrated. A document D to be copied is placed upon a transparent support platen P fixedly arranged in an illumination assembly, generally indicated by the reference numeral 10, positioned at the left end of the machine. Light rays from an illumination system are flashed upon the document to produce image rays corresponding to the informational areas. The image rays are projected by means of an optical system onto the photosensitive surface of a xerographic plate in the form of a flexible photoconductive belt 12 arranged on a belt assembly, generally indicated by the reference numeral 14.

45 The belt 12 comprises a photoconductive layer of selenium which is the light receiving surface and imaging medium for the apparatus, on a conductive backing. The surface of the photoconductive belt is made photosensitive by a previous step of uniformly charging the same by means of a corona generating device or corotron 13.

50 The belt is journaled for continuous movement upon three rollers 20, 21 and 22 positioned with their axes in parallel. The photoconductive belt assembly 14 is slidably mounted upon two support shafts 23 and 24 with the roller 22 rotatably supported on the shaft 23 which is secured to the frame of the apparatus and is rotatably driven by a suitable motor and drive assembly (not shown) in the direction of the arrow at a constant rate. During exposure of the belt 12, the portion ex-

posed is that portion of the belt running between rollers 20 and 21. During such movement of the belt 12, the reflected light image of such original document positioned on the platen is flashed on the surface of the belt to produce an electrostatic latent image thereon at exposure station A.

As the belt surface continues its movement, the electrostatic image passes through a developing station B in which there is positioned a developer assembly generally indicated by the reference numeral 15, and which provides development of the electrostatic image by means of multiple brushes 16 as the same moves through the development zone.

The developed electrostatic image is transported by the belt to a transfer station C whereat a sheet of copy paper is moved between a transfer roller and the belt at a speed in synchronism with the moving belt in order to accomplish transfer of the developed image solely by an electrical bias on the transfer roller. There is provided at this station a sheet transport mechanism generally indicated at 17 adapted to transport sheets of paper from a paper handling mechanism generally indicated by the reference numeral 18 to developed image on the belt at the station C.

After the sheet is stripped from the belt 12, it is conveyed into a fuser assembly, generally indicated by the reference numeral 19, wherein the developed and transferred xerographic powder image on the sheet material is permanently affixed thereto. After fusing, the finished copy is discharged from the apparatus at a suitable point for collection externally of the apparatus.

Further details regarding the structure of the belt assembly 14 and its relationship with the machine and support therefor may be found in the copending Application Ser. No. 102,312 assigned to the same assignee.

Referring now to FIGS. 2 and 3, the fuser assembly 19 of this invention is comprised of a fuser roller 30 and a pressure roller assembly, generally indicated as 32, including a pressure roller 34. The fuser roller 30 is formed of a suitable heat conductive material, such as copper and is provided with a source of heat 36, such as a quartz lamp, centrally positioned therein to heat the roller 30 to operational temperatures. The pressure roller 32 is mounted for rotation in end plates 38. A support bar 40 and a cam follower shaft 42 including suitable bearing means 44, are mounted to end plates 38. A pivot shaft 46 is affixed to and extends through the end plate 38 and is mounted for rotation in fuser frame assembly, generally indicated as 48.

The cam assembly, referring now to FIG. 4, generally indicated as 60, includes cams 62 mounted on a cam shaft 63, one end of which extends through the frame 48 and is provided with a gear 64 having an internally formed cammed surface 65. The gear 64 engages a drive gear 66, as more fully hereinafter described. A small cam 66 is positioned on the shaft in juxtaposition to a switch assembly, generally indicated as 68 including two switches. A linking latch 70 including a latching surface 72 is mounted for rotation to the frame 48, such as by screw 74 in a manner to contact the latching surface 72 at the termination of the loading cycle. One end of a spring 76 is affixed to the linking latch 70 with the other end affixed to the frame 48. A lever 80 is positioned below the linking latch 70 and is mounted for rotation to the frame 48 such as by screw 82. One end of the lever 80 is engage by a plunger 84 of a solenoid, generally indicated as 86. A torsion spring 88 (more

than one may be employed) is affixed to the cam shaft 63 and to the frame 48 to assist in the separation of the rollers at the termination of an image transfer mode.

In operation upon activation of the machine such as by the depression of a button by the operator, the element 36 is energized and heats the fuser roller 30 to an operational temperature range, at which time the machine shifts into a standby mode ready to be placed in an image transfer mode. Generation of a signal to place the machine in production energizes a clutch in a drive means, generally indicated as 90, to drive gear 66 which rotates gear 64 thereby causing the cam shaft 63 including cams 62 to rotate clockwise (as shown by the arrow) simultaneously winding torsion spring 88. Upon rotation through a predetermined angle, the cam 66 actuates the switch assembly 68, one switch therein de-energizes the clutch in the drive mechanism while the other switch energizes solenoid 86. Activation of the solenoid 86 causes the plunger 84 thereof to move upwardly thereby lifting lever 80 which raises latching link 70 to a point where the latching surface 72 engages the surface 65 of the gear 64 thereby locking the cam shaft 63 in the image fusing mode, i.e., the counter-clockwise movement of the cam shaft 63 is prevented. The pressure roller assembly thus moves from the position of the standby mode, illustrated by the dotted lines in FIG. 2, to the operational position illustrated by the solid lines therein.

Upon generation of a signal indicative of the completion of the image fusing mode, the solenoid is de-energized to permit the tensioning pressure of spring 76 to move the latching surface 72 downwardly away from the cammed surface 65 thereby permitting the cam shaft 63 to rotate counterclockwise by the force of spring 88 and natural inertia of the cams to return the pressure roller to its position in the standby mode of the machine.

While the operation of the fuser assembly has been described with reference to the unloading of the pressure roller in response to a signal (e.g., developed in response to a signal that the production run is completed), it is understood that unloading may also be effected automatically in response to a signal generated by other means, e.g., overheating of the heating element in the fuser roller 30, paper jams, etc.

While the instant invention as to its objects and advantages has been described herein as carried in specific embodiments thereof, it is not desired to be limited thereby; but it is intended to cover the invention broadly within the scope of the appended claims.

What is claimed is:

1. A fuser roller assembly for an electrostatographic machine including a fuser roller and a pressure roller, which comprises;
  - a. a pressure roller assembly in which said pressure roller is mounted for rotation, said pressure roller assembly being pivotally mounted in juxtaposition to said fuser roller within said machine and provided with cam following surface means;
  - b. a cam assembly including cam means disposed in said machine with said cam means thereof contacting said cam following surface means
  - c. drive means for rotating said cam assembly to cause said pressure roller assembly to move towards said fuser roller to a point where said pressure roller contacts said fuser roller in an image transfer mode of said machine;

- d. spring means for moving said pressure roller assembly away from said fuser roller, said drive means being adapted to place said spring means under torsional pressure during rotation of said cam means to said image transfer mode; and
  - e. locking means cooperable with said cam assembly after rotation of said cam assembly and said spring means through a predetermined angle to prevent counter rotation of said cam assembly and moving of said pressure roller assembly away from said fuser roller by said spring means.
2. The apparatus as defined in claim 1 wherein said locking means is engaged by movement of a solenoid means.
3. The apparatus as defined in claim 2 wherein said electrostatographic machine has means to provide a signal following said image transfer mode, and means to deactivate said solenoid means and disengage said locking means in response to said signal.
4. The apparatus as defined in claim 2 wherein said solenoid means is activated by a switch activated by a cam means mounted on a shaft of said cam assembly.
5. The apparatus as defined in claim 1 wherein said drive means is deactivated by a switch activated by a cam means mounted on a shaft of said cam assembly.

- 6. The apparatus as defined in claim 1 wherein said electrostatographic machine has means to provide a signal responsive to said image transfer mode; and means for activating said drive means in response to said signal.
- 7. In the fusing apparatus adapted for use with copy producing machines of the type comprising a roller pair in pressure relationship, with at least one of said rollers being heated, the combination of:
  - means supporting said rollers for movement relative to one another in to and out of pressure relationship;
  - drive means adapted when actuated to move said rollers into pressure relationship;
  - bias means adapted when loaded and activated to move said rollers apart, said drive means serving when actuated to load said bias means in preparation for subsequent release of said rollers;
  - means for locking said rollers in pressure relationship with said bias means in a preset loaded condition, ready to move said rollers apart; and
  - means to release said locking means and activate said bias means whereby said bias means moves said rollers apart.
